UNITED STATES PATENT OFFICE.

SAMUEL C. GOETTEL, OF CINCINNATI, OHIO.

GUARD FOR PRESSES.

1,365,315.

Specification of Letters Patent. Patented Jan. 11, 1921.

Application filed June 9, 1919. Serial No. 302,934.

To all whom it may concern:

Be it known that I, SAMUEL C. GOETTEL, a citizen of the United States, and a resident of Cincinnati, in the county of Hamilton and State of Ohio, have invented certain new and useful Improvements in Guards for Presses, of which the following is a specification.

My invention relates to guards for preventing injury of operators and others by machinery and more specially to guards of this character on printing presses and embossing presses and the like.

The object of my invention is to provide a very simple device of this kind which may be very readily attached to any usually constructed press of this kind and which will be very effective in operation to keep the operator's hands out from between the platen and the form or die or the like when these approach, and to avoid injury to the hands by the guard itself.

My invention consists in the combination of parts and in the details of construction and arrangement of parts as will herein-after be more fully described and claimed.

In the drawings:

Figure 1 is a partial side elevation of a printing press of well known construction having my invention applied thereto and showing the positions of the parts when the platen and form are about to come together, and showing, by dotted lines, the hand and arm of the operator to illustrate how the device acts thereon;

Fig. 2 is a similar view but with the press in feeding position and showing the hand of the operator, by dotted lines, in the act of feeding the press, to illustrate the free access which the device affords to the hand of the operator when the press is in this position;

Fig. 3 is a plan view of front parts of the press and my invention applied thereto;

Fig. 4 is a front elevation of the device embodying my invention detached from the press and with the press impression screws indicated by dotted lines and the triggers shown in section;

Fig. 5 is a detail perspective view of one of the triggers;

Fig. 6 is a similar view of one of the brackets;

Fig. 7 is a similar view of one of the rods; Fig. 8 is an enlarged top end view of the 55 rod;

Fig. 9 is a perspective view of part of a different kind of printing or embossing press and showing parts of a device embodying a modification of my invention as 60 applied to such a press;

Fig. 10 is a partial side elevation of a heavy embossing press with another modification of my invention applied thereto the positions of the parts during approach to 65 printing or embossing position being indicated by dotted lines;

Fig. 11 is a partial front elevation of the same;

Fig. 12 is a perspective view of this modified device detached from the press; and

Fig. 13 is a cross section on a plane corresponding to the line 13—13 of Fig. 12.

As shown in Figs. 1 to 6, inclusive, the printing press of a well known make has 75 the swinging bed 1, carrying the form 2, and drawn forward under the action of the main shaft 3 at the front through the medium of side arms 4 connected to the bed 1 and to the wheel 5 on the main shaft 3, 80 which wheel 5 carries on its inner face the cam 6 that tilts the rocker 7 through the medium of the rocker arm 8. As is well known in this kind of press the tilting of the rocker has such relation to the swinging of the bed 1 that the rocker 7 brings the platen 9 into printing position just before the form 2 reaches it, and so that the platen is tilted up for ready removal and insertion of the work during another and greater part of the 85 rotation of the wheel 5. Other details are concerned in the operation of the press, but what has been described is sufficient for explaining my invention.

As is well known in this and other kinds 95 of presses, the platen 9 is carried on the rocker 7 by four impression screws 10 which are screwed into bosses in the platen or its bridge piece and are screwed into ears 11 forming parts of the rocker 7, with lock-nuts 12 screwed up against the ears 11 to maintain the adjustment which is made by means of these screws, whereby exactly the right degree of pressure of the form on the platen is assured. The rocker 7 has trunnions in bearings 13 in the side frames 14 of

the press; being held in these bearings by caps or boxes 15 held to the frame 14 by cap screws 16 above and below.

- My improved guard, as applied to the 5 press of this construction, comprises brackets 17. Each one of these brackets 17 is made of heavy sheet metal and comprises a straight upright part 18 (Fig. 6) with lugs 19 and 20 at its upper and lower ends respectively, bent out horizontally, with alined 10 holes 21. This part 18 of each bracket is to be held at a respective end of the back part of the platen or bridge near the top thereof. From the front of this part 18 the bracket is 15 curved in toward the middle of the press and forwardly thereof and has, at its front end substantially at right angles to the front end part, an ear 22, having cut in from its free end down near its bottom a horizontal slot 23. These brackets are attached to the press 20 by loosening the lock-nuts 12 on the upper impression screws 10 and slipping the ears of the respective brackets in behind these nuts 12 with the screw 10 received in the slot 25. The bracket is adjusted horizontally so 25 that it clears adjacent parts of the press when swinging along with the rocker and platen, and then the nuts 12 are tightened to hold these brackets firmly and also continue to act as lock-nuts for the screws 10. These brackets may be thus attached without disturbing the impression adjustment of the parts if the nut 12 of only one of the screws 10 is loosened at a time. That is, the 30 mounting of one bracket should be completed before beginning the mounting of the other bracket; so that there will always be one securely held impression screw for the upper part of the platen.
- 40 The triggers 24 are fixed to the frame of the press at opposite sides of the rocker and platen. Each trigger is made of heavy sheet metal and comprises a bearing part 25 (Fig. 5) in the shape of an angle-bar running 45 from front to rear of the press with the upper member of the bar extending outward away from the platen, and a forwardly upwardly inclined part 26, having on its front end an ear 27 bent substantially at right angles to it, to stand upright, and having a downwardly opening slot 28. These triggers 24 are mounted by loosening the upper cap screw 16 of the rocker bearing and slipping the ear of the respective trigger down 50 behind the head of the screw 16 with the slot 28 receiving the screw. Then the cap screw is tightened, upon which the trigger will be held with its bearing part 25 near the lower lug 20 of the respective bracket 17.
- 60 The cross bar 29 is a simple angle bar with the upper horizontal member and the forward depending member and lying along the front upper edge of the platen or its bridge when the press is open for taking off and 65 feeding. This cross bar 29 extends past the

right and left ends of the platen and bridge and has depending rods 30 fixed in it near its end parts and extending down through the alined holes 21 in the lugs 19 and 20 of the respective brackets. Below the lower 70 lugs 20 these bars 30 are bent horizontally outward to form feet 31 that bear down on the tops of the bearing parts 25 of the respective triggers 24.

Preferably these rods 30 are attached to 75 the cross bar 29 so that they may be adjusted therewith transversely of the press to accurately fit this part of the device to the brackets 17 so that it will slide freely up and down therein. As here shown, the upper 80 end of each rod 30 has the reduced upwardly extending threaded part or stud 32 (Figs. 7 and 8) and, at the junction of this part 32 with the main part of the rod, parallel straight sides 33 are cut on the rod, which fit 85 in longitudinal slots 34 (Fig. 3) in the horizontal member of the cross bar 29 near the respective ends thereof. Cap-nuts 35 screw down on the studs 32 and clamp the rods 30 firmly to the cross bar 29 once the proper adjustment has been made. The parallel straight sides 33 fitting the slots 34 prevent the rods 30 from turning in the cross bar 29 and keep the feet 31 of the rods 30 extending laterally outward across the bearing parts 90 of the triggers as before described.

Light tension springs 36 have their upper ends connected to the depending member of the cross bar 29 in small holes therein near opposite ends thereof and have their lower 100 ends connected to the respective brackets 17 through small holes 36' in said brackets adjacent to the lower lugs 20 of said brackets.

When the rocker and platen tilt up for taking off and feeding they move upwardly 105 and forwardly relatively to the trigger 24. This allows the springs 36 to pull the cross bar 29 down close to the upper edge of the platen entirely out of the way of the operator. When the rocker and platen swing 110 downwardly into position to receive the impression their downward movement relatively to the trigger 24 causes the cross bar 29 to be pushed up due to the engagement of the feet 31 of the rods 30 with the bearing 115 part 25 of the trigger; this upward movement stretching the springs 36 which will then pull the cross bar 29 and rods 30 downward at the next upward and forward tilting of the rocker and platen. The just described 120 upward movement of the bar 24 begins along with the downward movement of the rocker and platen and becomes more rapid as the parts move more nearly at right angles to the bearing part 25 of the trigger; so that 125 by the time the bed 1 and form 2 have come near enough to the platen to endanger the hand of the operator, should it be between them, the cross bar will have risen so high that the hand in any such position will be 130

pushed up entirely away from the space between the platen and form as clearly indicated in Fig. 1.

Should the operator's hand get under the cross bar 29 this bar will then also effectively prevent access of the hand to the dangerous space; and if the hand is caught under this cross bar 29 between it and the upper edge of the platen or bridge during the upward and forward tilting of the parts there can be no serious injury to the hand because this cross bar is moving downward under no more force than that due to its own weight and the relatively light pull of the springs 36 thereon.

Fig. 9 shows part of a printing or embossing press wherein the side arm 4' is not spaced so far laterally outwardly from the rocker 7' and platen 9'. In this kind of a press the bed is generally stationary and the side arm 4', connected to a suitable crank in the bed part of the press, acts in combination with other mechanism to tilt the rocker 7' and platen 9' toward the form and bring the platen squarely against the form. The construction of such presses being well known it is deemed sufficient to merely illustrate the relation of the side arm 4' to the rocker 7' and platen 9' and the impression screw 10' entering the ear 11' of the rocker 7' and having the lock-nut 12'. It will be understood that these details are the same at the other side of the press and that another side arm 4' has the same position relative to them.

On this kind of press the feet 31 of the rods 30 engage with the upper sides of the side arms or connecting rods 4'; thus dispensing with the triggers 24 of the preceding example. The bracket 17' is similar to that of the preceding example but generally need not be so long nor so much off-set; it usually comprising merely the part 22' having the slot 23' and the upright part 18' directly joining the part 22' and having the upper and lower lugs 19' and 20' with the openings 21 through which the rod 30 slides up and down. This bracket is mounted by clamping it with the lock-nut 12' with the impression screw 10' received in the slot 23'. The cross bar 29 will be understood to be as in the preceding example and attached to the rods 30 in the same way to permit transverse adjustment of the rods to the bar; which, together with the transverse adjustment of the brackets 17' as permitted by their horizontal slots 23', makes it very convenient to fit the apparatus to practically any press of this kind. The bar 29 is pulled down by springs at each side such as the spring 36 in Fig. 9 which is hooked to the cross bar 29 and to the bracket 17' near the lower lug 20' thereof in a hole 36'.

Another press, which is similar to that of Fig. 9 in having the platen movable to a

stationary bed and having the side arms 4" close to the platen at each side, is partially illustrated in Figs. 10 and 11. This is a heavy embossing press; although it will be understood that the particular modification of my invention exemplified therewith is not peculiar to heavy presses nor presses used only for embossing.

My invention as applied to this press of Figs. 10 and 11 is similar to the example of Fig. 9 in that the rods 30" engage directly with the upper sides of the side arms 4".

The complete equipment according to this example is clearly shown in Fig. 12. These rods 30" slide up and down through bracket blocks 17" which are screwed to the opposite lateral edges of the rocker 7". The upper ends of the rods 30" have heads 37 and a round cross bar 29" has its ends fixed to these heads 37 by set screws 38 in the heads. Coiled tension springs 36" have their upper ends connected to respective heads 37 by screws 39 and their lower ends connected to respective blocks 17" by screws 40. These pull the cross bar 29" down when the rocker 7" and platen 9" swing upwardly and forwardly; and yield to permit the cross bar 29" to rise above the platen at it swings into impression-making position under the action of the side arms 4" and other mechanism on the rocker 7". The details of this other mechanism being well known in such presses need not be particularly described herein.

The device of this example of Figs. 10 and 11, so far as described, will constitute an effective guard for this kind of press just as in the other examples. However, I prefer to illustrate in connection with this kind of press additional mechanism in such a guard. This comprises a shutter 41 preferably made of sheet metal and pivoted on the round cross bar 29" to swing down or to swing rearwardly and upwardly across the space between the platen 9" and the form or die 2" as the platen approaches these. This shutter 41 extends almost the entire length of the bar 29" between the heads 37 of the rods 30" and is preferably attached to the bar 29" by means of hubs 42 at its ends and at its middle around which hubs it extends about half way and to which it is fixed by screws 43 (Fig. 13). This shutter 41 has the recesses 44 extending in from its free edge in the proper positions to receive the clamps 45 at the top of the bed when this shutter swings closely over said top. The parts of this free edge of the shutter 41 not removed in forming the recesses 44 preferably have the rounded beads 46 therealong to present a smooth surface which will not injure the hands of the operator or other objects coming in contact therewith.

This shutter 41 lies down behind the up-

per part of the platen and its rocker when these are tilted forwardly. Until the cross bar 29" has risen a considerable distance above the top of the rocker and platen the 5 rearward and upward swinging of the shutter 41 would be prevented by the shutter engaging said top. I therefore provide the means for swinging this shutter rearwardly and upwardly in such a way that it will 10 not act until the shutter has been carried high enough to clear said top. As here shown it consists of a rod 47 connected by a turn-buckle 48 to an eye-bolt 49 which is connected to another eye-bolt 50 fixed in one 15 of the end hubs 42 of the shutter. This rod 47 extends down the front of the rocker 7" through an eye-bolt 51 fixed in said front and the lower end of the rod 47 has a head 52 which will not pass through the eye-bolt 20 51. This head 52 is far enough below the eye-bolt 51 when the parts are in their lowered positions so that it will not engage with said eye-bolt 51 until the parts have risen far enough for the shutter to clear the top 25 of the rocker as before mentioned. By means of the turn-buckle 48 the length of this connection may be adjusted so that this engagement will occur just as soon as is practicable after this raised position has been 30 reached and thereby swing the shutter across the dangerous space as promptly as possible. For accelerating the return downward swinging of the shutter as the parts swing forwardly after the impression, I 35 prefer to provide a coiled spring 53 around the cross bar 29" inside the bent-around part of the shutter with one end 54 fixed in one of the end hubs 42 and the other end fixed by means of a screw 55 to the cross bar 40 29". Swinging of the shutter 41 thus twists this spring, and the spring in resuming its normal condition returns the shutter downwardly very quickly as the head 52 of the rod 47 recedes downwardly from the eye-bolt 51.

This shutter provides a still more effective barrier against protrusion of the operator's hand between the platen and the form or die. 50 It will be seen that the device constructed according to any of the examples is very readily attached to the press and no great skill is required for its proper adjustment; and when once properly adjusted it will not 55 readily get out of adjustment. The comparatively light pressure required to operate it makes it feasible to utilize very simple fastening means such as the clamping of the parts under the regular lock-nuts 60 or screw-heads of the press. When these are drawn up as tight as they must be to perform their normal functions in the press they will effectively prevent any movement of the parts of my invention out of their

correctly adjusted position under the normal strains incident to their operation. 65

While certain examples of my invention are shown with certain respective examples of presses it will be understood that any example of my invention is applicable to any one of the presses; and by minor modifications my invention of any of the examples is applicable to practically any printing press, embossing press or the like, and will effectively function in the desired manner in 70 connection with the operation of any such press or other machine of that kind. By having the parts of the device adjustable the variety of makes and sizes of machines to which any given outfit is applicable is considerably increased as is also the ease with 75 which the outfit may be applied to any given machine.

While certain constructional details are deemed preferable in connection with my invention, and I have shown and described these rather specifically in elucidating the construction and use of my invention, as is required, I do not wish to be understood as being limited to such precise showing and 80 description, but having thus fully described my invention, what I claim as new and desire to secure by Letters Patent is:

1. In combination with a platen and an impression screw therefor and a lock nut 95 for said screw, a bracket clamped by said lock nut and having guide means near one side of said platen, a guard element guided by said guide means, to move toward or from said platen, and means causing said 100 guard element to move away from said platen upon movement of said platen toward pressing position.

2. In combination with a platen, its rocker, an impression screw holding said 105 platen to said rocker, a lock nut for said impression screw, a bearing for said rocker, and a cap screw for said bearing, a bracket clamped by said lock-nut and having guide means near one side of said platen, a trigger clamped by said cap screw and having a bearing part near said guide means, and a guard element guided by said guide means and bearing upon said trigger bearing part to be moved away from said platen upon 110 movement of said platen toward pressing position.

3. In combination with a platen, its rocker, an impression screw holding said platen to said rocker, a lock nut for said 120 impression screw, a bearing for said rocker, and a cap screw for said bearing, a bracket clamped by said lock nut and having guide means near one side of said platen, a trigger clamped by said cap screw and having a 125 bearing part near said guide means, a guard element guided by said guide means and bearing upon said trigger bearing part to

- be moved away from said platen upon movement of said platen toward pressing position, and yieldable means to return said guard element toward said platen upon return of said platen from pressing position. 5 thereof and lock nuts for said screws, brackets clamped by the respective lock nuts and having guide means near respective lateral sides of said platen, rods sliding in the respective guide means, a guard element lying along the upper part of said platen and 65 having its opposite end parts attached to said rods, means upon which said rods bear upon movement of said platen toward pressing position, whereby said rods move said guard element away from said platen during said movement of said platen, and springs connected to the respective brackets and to respective end parts of said guard element to return said guard element toward said platen upon return of said platen from 70 pressing position.
4. In combination with a platen, its rocker, an impression screw holding said platen to said rocker, a lock nut for said impression screw, a bearing for said rocker, 10 and a cap screw for said bearing, a bracket clamped by said lock nut and having guide means near one side of said platen, a trigger clamped by said cap screw and having a bearing part near said guide means, a 15 rod sliding in said guide means and bearing upon said trigger bearing part, and a guard element attached to said rod to lie along said platen and be moved away from said platen by said rod upon movement of said platen 20 toward pressing position.
5. In combination with a platen, its rocker, an impression screw holding said platen to said rocker, a lock nut for said impression screw, a bearing for said rocker, 25 and a cap screw for said bearing, a bracket clamped by said lock nut and having guide means near one side of said platen, a trigger clamped by said cap screw and having a bearing part near said guide means, a rod 30 sliding in said guide means and bearing upon said trigger bearing part, a guard element attached to said rod to lie along said platen and be moved away from said platen by said rod upon movement of said platen 35 toward pressing position, and yieldable means to return said guard element toward said platen upon return of said platen from 40 pressing position.
6. In combination with a movable press element, a guard element adapted to lie along the upper part of said press element, means at opposite lateral sides of said press element to cause said guard element to move away from said press element upon movement of said press element toward pressing 45 position, and means for adjusting said guard element and said means relatively to each other laterally of said press element.
7. In combination with a platen and impression screws near respective lateral sides 50 thereof and lock nuts for said screws, brackets clamped by the respective lock nuts and having guide means near respective lateral sides of said platen, rods sliding in the respective guide means, a guard element lying along the upper part of said platen and having its 55 opposite end parts attached to said rods to be moved away from said platen by said rods upon movement of said platen toward pressing position, said brackets having horizontal slots receiving said impression screws where said brackets are clamped by said lock nuts, whereby said brackets are adjustable laterally relatively to said triggers.
8. In combination with a platen and impression screws near respective lateral sides 60 of said platen during said movement of said platen.
9. In combination with a platen and its rocker, impression screws holding said platen to said rocker, lock nuts for the respective screws, bearings for said rocker 65 at opposite lateral sides thereof and cap screws for the respective bearings, brackets clamped by the respective lock nuts and having guide means near respective opposite lateral sides of said platen, triggers 70 clamped by the respective cap screws and having bearing-parts near the respective guide means, rods sliding in the respective guide means and bearing upon the respective trigger bearing-parts, and a guard element lying along the upper part of said platen and having its 75 opposite end parts attached to said rods to be moved away from said platen by said rods upon movement of said platen toward pressing position.
10. In combination with a platen and its rocker, impression screws holding said platen to said rocker, lock nuts for the respective screws, bearings for said rocker at opposite lateral sides thereof and cap screws 80 for the respective bearings, brackets clamped by the respective lock nuts and having guide means near respective opposite lateral sides of said platen, triggers clamped by the respective cap screws and having bearing-parts near the respective guide means, rods sliding in the respective guide means and bearing upon the respective trigger bearing-parts, and a guard element lying along the upper part of said platen and having its 85 opposite end parts attached to said rods to be moved away from said platen by said rods upon movement of said platen toward pressing position.
11. In combination with a platen and its rocker, impression screws holding said platen to said rocker, lock nuts for the respective screws, bearings for said rocker 90 at opposite lateral sides thereof and cap screws for the respective bearings, brackets clamped by the respective lock nuts and having guide means near respective opposite lateral sides of said platen, triggers clamped by the respective cap screws and having bearing-parts near the respective guide means, rods sliding in the respective guide means and bearing upon the respective trigger bearing-parts, and a guard element lying along the upper part of said platen and having its 95 opposite end parts attached to said rods to be moved away from said platen by said rods upon movement of said platen toward pressing position.
12. In combination with a platen and its rocker, impression screws holding said platen to said rocker, lock nuts for the respective screws, bearings for said rocker 100 at opposite lateral sides thereof and cap screws for the respective bearings, brackets clamped by the respective lock nuts and having guide means near respective opposite lateral sides of said platen, triggers clamped by the respective cap screws and having bearing-parts near the respective guide means, rods sliding in the respective guide means and bearing upon the respective trigger bearing-parts, and a guard element lying along the upper part of said platen and having its 105 opposite end parts attached to said rods to be moved away from said platen by said rods upon movement of said platen toward pressing position.
13. In combination with a platen and its rocker, impression screws holding said platen to said rocker, lock nuts for the respective screws, bearings for said rocker 110 at opposite lateral sides thereof and cap screws for the respective bearings, brackets clamped by the respective lock nuts and having guide means near respective opposite lateral sides of said platen, triggers clamped by the respective cap screws and having bearing-parts near the respective guide means, rods sliding in the respective guide means and bearing upon the respective trigger bearing-parts, and a guard element lying along the upper part of said platen and having its 115 opposite end parts attached to said rods to be moved away from said platen by said rods upon movement of said platen toward pressing position, said brackets having horizontal slots receiving said impression screws where said brackets are clamped by said lock nuts, whereby said brackets are adjustable laterally relatively to said triggers.
14. In combination with a platen and its rocker, impression screws holding said platen to said rocker, lock nuts for the respective screws, bearings for said rocker 120 at opposite lateral sides thereof and cap screws for the respective bearings, brackets clamped by the respective lock nuts and having guide means near respective opposite lateral sides of said platen, triggers clamped by the respective cap screws and having bearing-parts near the respective guide means, rods sliding in the respective guide means and bearing upon the respective trigger bearing-parts, and a guard element lying along the upper part of said platen and having its 125 opposite end parts attached to said rods to be moved away from said platen by said rods upon movement of said platen toward pressing position.

- at opposite lateral sides thereof and cap screws for the respective bearings, brackets clamped by the respective lock nuts and having guide means near respective opposite 5 lateral sides of said platen, triggers clamped by the respective cap screws and having bearing-parts near the respective guide means, rods sliding in the respective guide means and bearing upon the respective trigger bearing-parts, and a guard element lying along the upper part of said platen and having its opposite end parts attached to said rods to be moved away from said platen by said rods upon movement of said platen 10 toward pressing position, said guard element having slots through which it is attached to said rods as aforesaid, whereby said rods and brackets are adjustable laterally relatively to said guard element.
12. In combination with a platen and its rocker, impression screws holding said platen to said rocker, lock nuts for the respective screws, bearings for said rocker at opposite lateral sides thereof and cap screws 25 for the respective bearings, brackets clamped by the respective lock nuts and having guide means near respective opposite lateral sides of said platen, triggers clamped by the respective cap screws and having bearing-parts near the respective guide means, rods sliding in the respective guide means and bearing upon the respective trigger bearing-parts, and a guard element lying along the upper part of said platen and having its opposite end parts attached to said rods to be moved away from said platen by said rods upon movement of said platen toward pressing 30 position, said brackets having horizontal slots receiving said impression screws where 40 said brackets are clamped by said lock nuts, whereby said brackets are adjustable laterally relatively to said triggers, and said guard element having slots through which it is attached to said rods as aforesaid, whereby said rods and brackets are adjustable laterally relatively to said guard element.
13. In combination with a movable press element, a guard element lying along said press element, mounted to slide away from said press element and to swing over said press element in pressing direction, and means to first slide said guard element and then swing said guard element as aforesaid, upon movement of said press element toward pressing position.
14. In combination with a movable press element, a guard element lying along said press element, mounted to slide away from said press element and to swing over said press element in pressing direction, means to first slide said element and then swing said element as aforesaid, upon movement of said press element toward pressing position.
15. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after initial upward sliding of said rod, and means to cause said rod to slide up when said press element moves toward pressing position. 70
16. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after initial upward sliding of said rod, and means to cause said rod to slide up when said press element moves toward pressing position. 80
17. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after initial upward sliding of said rod, and means to cause said rod to slide up when said press element moves toward pressing position, said guard element lying below said top of said press element during said initial upward sliding, and then being swung over said top upon engagement of the aforesaid engaging means 90 after said initial sliding.
18. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after initial upward sliding of said rod, means to cause said rod to slide up when said press element moves toward pressing position, and yieldable means to swing said guard element in return direction and yieldable means to slide said guard element down, upon return of said press element from pressing position. 100
19. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after initial upward sliding of said rod, and means to cause said rod to slide up when said press element moves toward pressing position. 110
20. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after initial upward sliding of said rod, and means to cause said rod to slide up when said press element moves toward pressing position. 115
21. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after ini- 120
22. In combination with a movable press element, a rod slidable up and down on said press element, a guard element pivoted to said rod and lying along the top of said press element, a tension element connected to said guard element, engaging means on said press element, engaging means on said tension element engaging with the engaging means on the press element to cause swinging of said guard element, after ini- 125

tial upward sliding of said rod, means to cause said rod to slide up when said press element moves toward pressing position, said guard element lying below said top of 5 said press element during said initial upward sliding, and then being swung over said top upon engagement of the aforesaid engaging means after said initial sliding, and yieldable means to swing said guard element from over said press element and 10 yieldable means to slide said guard element down, upon return of said press element from pressing position.

SAMUEL C. GOETTEL.
